UNITED STATES PATENT OFFICE.

WILLIAM S. BENJAMIN, OF SEATTLE, WASHINGTON.

ROCK-DRILLING MACHINE.

1,087,632.

Specification of Letters Patent.

Patented Feb. 17, 1914.

Application filed June 17, 1912. Serial No. 704,048.

To all whom it may concern:

Be it known that I, WILLIAM S. BENJAMIN, a citizen of the United States, residing at Seattle, in the county of King and State 5 of Washington, have invented certain new and useful Improvements in Rock-Drilling Machines, of which the following is a specification.

This invention relates to improvements in 10 rock drilling machines, and is intended more especially for submarine work, although it may advantageously be used in other situations.

The object of the invention is to provide 15 an efficient machine of this character which will be of simple construction, easy to operate, and not liable to become deranged when subjected to rough usage.

The invention consists in certain structural features and combinations thereof, substantially as hereinafter described and claimed.

In the accompanying drawings, Figure 1 is a longitudinal vertical section of an embodiment of the present invention. Fig. 2 is a view of the same shown partly in elevation and partly in section.

In carrying out my invention, I provide a bored barrel which, for convenience of 30 manufacture, is desirably composed of two parts 1 and 2 rigidly connected together. Extending into the bore 3 of the lower barrel part 2 is a reciprocating percussive member 4, and a heavy piston 5, or hammer as it 35 will hereinafter be called, within the other part 1. Detachably secured, as by pins 6, to the lower end of the percussive member is a head 7 which is provided at its center with a socket 8 for a drill-bit 9 of a length 40 to extend from a distance below said head up into a recess 10 provided in the adjacent end of said member. The drill-bit 9 is desirably made of a single piece and is formed with a plurality of radially disposed 45 blades 9' at its lower end and above such blades the bit is provided with an axially disposed passage 9² which communicates with the various angular spaces afforded between said bit blades. The head 7 has in 50 its under side a number of grooves 11 arranged radially or approximately so, to the axis of the head. Removably seated within these head-grooves are cutter elements 12 which are each secured in its respective 55 grooves in any suitable manner as by a key 13.

15 represents a cover plate for the barrel

part 1 and extending axially through this plate, the piston 5 and the member 4 is a pipe 16 which extends from the bit 9 to an elevation in proximity to the surface of the water in which the machine is operating. 60 Packing rings 17 and 17' are provided between the inner and outer peripheral walls of member 4 and hammer 5 to prevent leakage of the actuating fluid between these 65 parts and the pipe and barrel walls.

Rigidly connected to the barrel or to the cover plate 15 thereof is a cylinder 18 which is divided by a partition 19 into an upper chamber 20 and a valve chamber 21 there- 70 below.

22 represents a pipe for the motive fluid, preferably compressed air, supplied to the upper end of chamber 21, from an air compressor positioned upon a float or vessel 75 (not shown) which likewise carries hoisting apparatus for controlling the lines 23 whereby the machine is suspended while being lowered to the surface of the rock to be drilled. After being so lowered sufficient 80 tension is maintained on the lines to retain the machine in upright position until at least it has entered the rock sufficiently to be held upright by the drilled hole. Adjacent to the lower end of the valve chamber 85 21 is a port 24 which is connected by a passage 24' with the bore of the barrel at or about the plane of the upper end of the member 4 when the same is in its uppermost position with respect to the barrel. In- 90 termediate the openings of said supply pipe and the passage 24' into the valve chamber, the latter is provided with an exhaust port 25 which leads into a pipe 25' which dis- 95 charges into the pipe 16 and serves as an ejector element whereby the column of water within the pipe 16 is induced to ascend by the discharges from the pipe 25' and whereby the comminuted rock, as broken away by the drill bit 9 and cutter 100 elements, are carried upwardly with the water and discharged from the upper end of the pipe 16.

In order to prevent the water from flowing through pipe 25' into the valve chamber, I provide a non-return valve in this pipe positioned within a nozzle end 25² of the pipe. In proximity to the upper end of the valve chamber 21 is a port 27 which communicates by a passage 27' and a port 110 27² with the barrel-bore at a short distance below the cover plate 15 of same. At a

2
higher elevation than the port 24² of passage 24' is a port 28 of a passage 28' which extends to an opening 28² near the upper end of the chamber 20. Fitted for reciprocation within this chamber is a piston 29 which is connected by a stem 30 extending through a packing box provided in the partition 19 with a slide valve 31 provided in the chamber 21. Interposed between the piston 29 and said partition is a helical spring 32 which tends to urge the piston and the slide valve upwardly to occupy the positions in which they are represented in Fig. 1. As, illustrated, said slide valve consists of a cylindrical body of a length approximating the distance between the port 22² of the air supply pipe 22 and the port 24² of the passage 24' which communicates with the barrel-bore. The valve is characterized by having a by-pass 31' extending through its entire length and by being provided with a peripheral recess 31² of sufficient length to connect the ports 24 and 25 of the respective passages when the valve is at the lower end of its travel as shown in Fig. 2.

4' represents a collar formed on or rigidly secured to said percussive member and is operable within a counter-bore 3' of the barrel to limit the strokes of the percussive member by encountering an end of such counter-bore at the termination of one stroke and being, upon occasion, arrested at the conclusion of the other stroke, by an elastic bumper-ring 33 which is supported by an annulus 35 secured to the under side of the barrel as indicated in Fig. 1. The bumper ring 33 is, however, brought into play only when the machine is actuated while away from the work and is designed to prevent any undue impact being then delivered to the machine structure.

An exhaust pipe 36 leads from the upper end of the chamber 20 to the main exhaust pipe 25'. Included in the pipe 36 is an adjustable valve 36' whereby the discharge opening through this pipe may be regulated to a relatively small size and through which the air which may be present within the chamber will flow sluggishly therefrom and consequently act as a cushion to retard the upward movements of the piston 29 in opposition to the power exercised by the spring 30.

The operation of the afore described portion of the invention is as follows: Assuming the various parts are in the positions in which they are represented in Fig. 1, compressed air is supplied through pipe 22 to the upper end of the chamber 21 whence it flows through the by-pass 31' of valve 31 to the underside of the latter and thence is led by passage 24' to the underside of the hammer 5 to effect the raising of the same. As hammer 5 moves upwardly the port 28 is exposed and the actuating fluid escapes by way of passage 28' into the upper end of

chamber 20, resulting in the building up of a fluid pressure above piston 29 which will overcome the power of spring 30 and cause the piston to descend accompanied by the valve 31 into the position which they occupy in Fig. 2. During the ultimate portion of the downstroke of the valve, however, the port 27 has been closed with respect to the flow of air from the upper end of barrel-port 1 to the exhaust pipe 25'. The residual air within the barrel and above the hammer is compressed by the further upward travel of the hammer and affords a cushion to gradually arrest the motion of the hammer and finally reacting, and supplemented by the weight of the hammer, the latter is forced down below the port 27² whereupon and by reason of the port 27 being now uncovered by valve 31 air under pressure is delivered through passage 27 to the space above the hammer to accelerate the speed of the hammer and thereby impel it with relatively high velocity and power against the percussive member 4 which, in turn, strikes, so to speak, the bottom of the hole being bored. As the hammer descends the air therebelow will obviously escape through the passage 24' about the peripheral recess 31² of the valve (see Fig. 2) and into exhaust pipe 25'. During the downward, or striking, movement of the hammer the air previously admitted to the upper end of chamber 20 escapes through the pipe 36 whereupon the spring 32 asserts its power to elevate the piston 29 and thus restore the valve 31 to the position which it occupied at the beginning of the above described cycle of operation.

In the operation of this machine, the weight thereof bears against the work, and when the hammer 5 strikes the percussive member 4 the latter is first driven down followed by the barrel and the parts connected thereto and delivering a second blow to the percussive member through the medium of the collar 4'. By such devices, the recoil of the percussive member is practically eliminated and the drilling of a hole with a machine is rendered much more rapid, as not only the momentum of said member is utilized but the weight of the entire machine is applied therewith or supplemented thereto.

What I claim, is:—

1. In a drilling machine, the combination of a barrel, a piston hammer and a percussive member in the barrel, a collar provided on said member and engageable by the barrel and means provided on the barrel and engageable by said collar for limiting the forward stroke of said member, a valve chamber, passages connecting the interior of the barrel with the valve chamber, inlet and outlet openings for said chamber, a valve in said chamber for controlling said

- passages and openings, a spring operatively connected with the valve for yieldingly holding said valve in position to afford a supply of the motive fluid to said barrel to effect the elevation of the piston-hammer, and means controlled by the latter when it approaches the upper end of its reverse stroke whereby the motive fluid is applied to the piston hammer to effect the forward stroke of the same.
2. In a drilling machine, the combination with a barrel, a piston hammer arranged for reciprocatory movements therein and a percussive member extending into said barrel a cylinder secured to said barrel and divided into two chambers, a passage from a point adjacent the bottom of said lower chamber to a bottom point in said barrel, a passage from a point removed from the top of said lower chamber to a point slightly removed from the top of said lower chamber, ports provided for the supply and exhaust of the motive fluid to and from said lower chamber positioned adjacent the top and the middle points thereof respectively, a valve in the lower chamber having a by-pass therethrough and a peripheral recess therearound, a piston in the upper one of said chambers, a stem operatively connecting the valve with said piston, a spring acting to elevate said piston and valve, a passage connecting the interior of the barrel with the upper chamber and above the piston therein, and a valve-controlled exhaust passage leading from the upper end of said upper chamber, substantially as and for the purposes described.
3. In a drilling machine, the combination
- with a barrel, a piston hammer arranged for reciprocatory movements therein, and a percussive member extending into said barrel, a cylinder secured to said barrel and divided into two chambers, a passage from a point adjacent the bottom of said lower chamber to a bottom point in said barrel, a passage from a point removed from the top of said lower chamber to a point slightly removed from the top of said lower chamber, ports provided for the supply and exhaust of the motive fluid to and from said lower chamber positioned adjacent the top and the middle points thereof respectively, a valve in the lower chamber having a by-pass therethrough and a peripheral recess therearound, a piston in the upper one of said chambers, a stem operatively connecting the valve with said piston, a spring acting to elevate said piston and valve, a passage connecting the interior of the barrel with the upper chamber and above the piston therein, a valve-controlled exhaust passage leading from the upper end of said upper chamber.

Signed at Seattle, Washington, this 6th day of June, 1912.

WILLIAM S. BENJAMIN.
